UNITED STATES PATENT OFFICE.

OLIVER S. SLEEPER, OF BUFFALO, NEW YORK, ASSIGNOR TO THE BUFFALO FOUNDRY & MACHINE COMPANY, OF BUFFALO, NEW YORK, A CORPORATION OF NEW YORK.

VACUUM-DRYER.

1,074,903.

Specification of Letters Patent.

Patented Oct. 7, 1913.

Application filed June 6, 1910; Serial No. 565,835. Renewed May 12, 1913. Serial No. 767,189.

To all whom it may concern:

Be it known that I, OLIVER S. SLEEPER, a citizen of the United States, residing at Buffalo, in the county of Erie and State of New York, have invented new and useful Improvements in Vacuum-Driers, of which the following is a specification.

This invention relates to a vacuum drying apparatus for evaporating or desiccating milk and other liquids containing solids from which the moisture is to be expelled and more particularly to an apparatus for this purpose in which the condensate is delivered on a rotatable drum and scraped therefrom after being dried.

One of the objects of this invention is to produce a vacuum drier of this character having means for delivering the condensate to the drying drum by means which can be cleaned more readily than those heretofore employed for this purpose and which present the condensate to the drum so as to reduce frothing to a minimum and insure the delivery of a film of uniform thickness to the drum.

Another object of this invention is to provide means whereby the dried material which is removed from the drum is relieved from the suction effect of the device which removes the vapor from the condensate while on the drum.

My invention has the further object to provide auxiliary heating means for preventing condensation on the wall of the drying chamber adjacent to the scraper while the apparatus is comparatively cold when starting the same and thus prevent liquid from getting into the receptacle for the dried material.

In the accompanying drawings consisting of 5 sheets: Figure 1 is a vertical longitudinal section of a vacuum drying apparatus embodying my improvements. Figs. 2 and 3 are vertical transverse sections, on an enlarged scale, of the same in lines 2-2, and 3-3, Fig. 1, respectively. Figs. 4 and 5 are horizontal sections in lines 4-4 and 5-5, Fig. 2, respectively. Fig. 6 is a fragmentary horizontal section, on an enlarged scale, in line 6-6, Fig. 2. Figs. 7, 8, 9 and 10 are fragmentary vertical sections on the correspondingly numbered lines in Fig. 6. Fig. 11 is a fragmentary transverse section, on an enlarged scale, showing part of the

means for feeding the milk to the heating or drying drum.

Similar letters of reference indicate corresponding parts throughout the several views.

In its general organization my improved drier comprises a vacuum or drying chamber A and a drying or heating drum B which rotates about a horizontal axis within the drying chamber. The vacuum chamber is formed by an inclosing casing or housing comprising a body a constituting the longitudinal sides, top and bottom of the casing, and two heads a¹, a² which are detachably secured to opposite ends of the body and form the ends of the casing.

The lower part of the casing is constructed to form a catch basin or reservoir C for the liquid to be dried or desiccated and a residuum receiving and delivery chamber or spout D which is adapted to receive the dried product of the liquid. The liquid reservoir and receiving chamber are arranged lengthwise side by side and separated by an intervening upright wall or partition d, as shown in Fig. 2. At its top the casing of the drying chamber is provided with a vapor outlet e which is connected with a vacuum pump, condenser or other exhausting device for removing the vapors from the interior of the drying chamber.

The drying drum comprises a horizontal cylindrical body b and two heads b¹, b² secured to opposite ends of the body and provided with hollow trunnions f, f¹ which are journaled in bearings F, F¹ on the heads a¹, a² of the drying chamber.

Rotation of the drum in the direction of the arrow Fig. 2, may be effected by any suitable means. The heating of the drum may also be effected by various means but preferably those which are shown in the drawings and which comprise a stationary steam supply pipe G entering one hollow trunnion and a stationary delivery pipe g for the water of condensation arranged in the other trunnion. The water of condensation is caught by a drain scoop h arranged adjacent to the bore of the drum and delivered to the outlet trunnion of the drum by a return pipe h¹ in a manner common in this type of driers.

The liquid to be dried is applied to the drum in the form of a thin film or coating on the underside of the same and is carried

upwardly on one side of the drum and downwardly on the other side thereof during which movement of the material the moisture therein is evaporated and the solid ingredients contained therein remain clinging to the periphery of the drum.

My improved means for feeding the liquid to the drum are constructed as follows:—I represents a liquid feed pan or nozzle arranged below the drum and comprising a bottom i^1 which is preferably curved concentric with the drum, a front longitudinal flange or wall i^1 rising from the front longitudinal edge of the bottom i^1 and stopping at its upper edge short of the periphery of the drying drum, a rear longitudinal flange or wall i^2 rising from the rear longitudinal edge of the bottom i^1 and engaging with the periphery of the drum, a strip or bar i^4 for reinforcing the rear wall i^2 secured to the front side of the latter and the bottom and also engaging with the periphery of the drum for increasing the wearing surface, and two end flanges or walls i^3 which rise from opposite transverse edges of the bottom and engage at their upper edges with the periphery of the drum. The front wall i^1 is preferably arranged a greater distance from the vertical center of the drum than the rear wall i^2 , as shown in Fig. 2. This delivery pan extends the full length or nearly so of the drum and is mounted on the rear ends of a plurality of vertically swinging rock arms J which are secured at intervals at their front ends to a horizontal rock shaft j arranged lengthwise in the drying chamber below the drum and journaled at its opposite ends in stuffing box bearings j^1 arranged on the heads of the drying chamber. Upon turning this shaft and its arms in one direction the pan may be swung downwardly away from the drum and into a position in which the same may be thoroughly cleaned and kept in sanitary condition, while upon turning the shaft and arms in the opposite direction the pan may be swung upwardly into its operative position relatively to the drum. The pan may be thus raised and lowered by means of a hand lever K secured to one end of the shaft outside of the casing and the pan is held in its operative position by means of a clamping bolt or screw k^1 which secures the hand lever against a lug k^2 on the adjacent head of the casing, as shown in Fig. 4. Below the pan and preferably vertically in line with the axis of the drying drum is arranged a horizontal longitudinal manifold which is preferably constructed of two sections L , L which are arranged in line and each of which is connected with the underside of the pan by a plurality of upright nipples l . The outer end of each manifold section L is closed by a cap l^1

which is removably secured thereto so as to provide access to the interior thereof for cleaning the same.

Means are provided for supplying the manifold with the liquid material to be evaporated which means permit of freely raising and lowering the pan and associated parts without disturbing the liquid supply connections and are constructed as follows:—M represents a hollow bracket arranged transversely within the drying chamber and secured at its outer end to the front wall of the casing while its inner end is provided with a hollow cylindrical knuckle m through which the pan shifting shaft J passes concentrically. N represents a liquid supply pipe extending through the bracket M and connected at its inner end with the interior of the knuckle thereof while its outer end is connected by a T-fitting M^1 with a pipe n containing a valve n^1 whereby liquid from a main supply tank or reservoir may be delivered to the pan and also with a return pipe n^2 which connects by an intermediate conduit with a drain pipe n^3 at the bottom of the casing whereby the liquid in the reservoir in the drying chamber may be delivered to the pan. Upon detaching the T-fitting M^1 from the supply pipe M the interior of the latter is accessible for cleaning the same from the exterior of the casing. O represents a hollow swinging arm or pipe provided at its outer end with a hollow knuckle o^1 , which is arranged adjacent to the knuckle m and is traversed concentrically by the pan shifting shaft J while its inner end is connected on its opposite sides with the inner ends of the manifold sections L , L . The inner end of the swing pipe is provided with a cap o^2 which is removably connected therewith so as to afford access to the interior of this pipe for cleaning the same. The opposing sides of the knuckles of the swing pipe and the bracket are connected by a rotatable joint which permits the swing pipe to be turned relatively to the bracket without disturbing the passage between the same, this connection consisting preferably of an annular rib o^3 formed concentrically on the respective side of the movable knuckle o^1 and engaging with a corresponding groove in the opposing side of the stationary knuckle m , as shown in Figs. 6 and 10. The opposite side of the movable knuckle o^1 is closed by a cap p which is removably secured thereto so as to render the interior of both knuckles accessible for cleaning. The two knuckles are held in operative relation to each other and still permit the cap p to be freely attached to or detached from the movable knuckle by means of a collar q secured to the pan shifting shaft J and engaging with the outer side of the fixed knuckle m , a cross

bar Q engaging with that side of the adjacent pan supporting arm which faces the movable knuckle, stay rods or bolts q^1 arranged parallel with the shaft J on opposite sides of the cap p and each having a screw connection at opposite ends with the movable knuckle and one end of the cross bar Q, and jam nuts q^2 applied to the stay bolts and bearing against the movable knuckle and the cross bar.

During the operation of the machine the liquid to be dried passes from the supply pipe N successively through the knuckles, swing pipe, manifolds and nipples into the pan and after filling the latter overflows the front longitudinal wall thereof and drops into the reservoir in the bottom of the casing, from which latter the surplus liquid is drawn off through the pipe n^3 and returned by a pump of any suitable construction to the return pipe n^2 to be again circulated in the manner described. As the lower part of the drum sweeps over the pan it dips into the stream of liquid in the latter and picks up a thin film, coating or layer thereof. The film of liquid adhering to the exterior of the drum is dried by the heat within the same as the liquid moves upwardly on the front and downwardly on the rear side of the drum. Before the dried material on the drum reaches the liquid feeding position this material is removed from the periphery of the drum by a scraper or doctor R which projects upwardly from the partition d and which directs the same into the product receiving chamber D, thereby clearing the drum preparatory to applying another coat of liquid thereto. The operation of circulating the liquid, feeding the same to the drum and removing the dried residuum proceeds continuously while the machine is in full operation. From the product receiving chamber the material is delivered through an outlet in its bottom into a box S in which the material accumulates and from which it is removed from time to time as desired. The temperature of the liquid in the reservoir C may be maintained at the desired degree by means of a heating device comprising coils t which are arranged in the lower part of the reservoir C and through which steam, hot water or other heating medium may be circulated. Access to the interior of the drying chamber for cleaning the parts therein may be had through an opening which is formed in one of the casing heads and which is normally closed by a cover or door t^1 . As the dried product is scraped from the descending side of the drum the same has the form of large sheets which are liable to pile up on the rods u of the scraper adjusting mechanism and which extend across the product delivery spout. To prevent this dried sheets or flakes are broken up into small particles by means of a disint-

egrator comprising a longitudinal beater shaft v arranged above the adjusting rods u and a plurality of beaters v¹ mounted on said shaft, as shown in Figs. 2 and 4. While scraping the dried material from the drum and, reducing the same by means of the beaters, considerable light and fine dust is produced which in the absence of any provision to prevent it would be carried away with the vapors over the top of the drum 75 and also around the ends of the same where there is considerable space owing to the outward dishing of the casing heads a¹, a² which are thus made to permit access to the ends of the drum for cleaning. To prevent such light particles of dried material from being carried away with the vapors and thus necessitate additional work for their recovery, if it is not desired to lose the same, means are provided which comprise a baffle plate W which is preferably inclined and extends both transversely and lengthwise practically across the space between the drum and the casing on the descending side of the drum, as shown in Figs. 2 and 5. This baffle is 80 preferably pivoted at its upper end on the adjacent wall of the casing and connected at its lower end with said wall by braces w arranged below the baffle.

In order to prevent the light and fine particles of dried material from being drawn from the product chamber or delivery spout around the ends of the drum and to the vapor outlet, each of the end heads of the drying chamber is provided with a web-shaped baffle x which extends from the upper end of the partition d, along the adjacent transverse edge of the scraper, the periphery of the drum and the transverse edge of the peripheral baffle W to the adjacent side wall 100 of the casing of the drying chamber, as shown in Figs. 2, 3 and 4. These end baffles together with the peripheral baffle thus reduce the suction of the exhausting device from the space between the drum and the 105 casing wall adjacent to the scraper, thereby permitting the light and fine dry particles to settle in the spout and pass to the receiving box with the larger heavier particles, whereby the output of the machine is increased accordingly.

Inasmuch as the space within the casing opposite the scraper and below the baffles is nearly cut-off from the exhaust device, the outer wall of the casing adjacent to this space, in the absence of any provision to prevent it, would remain cool for sometime after starting the machine and thereby condense the vapors on this wall which vapors would run down into the receptacle for the 120 dried material which is objectionable. To avoid this a supplemental heating device is provided in the space between the drum and drying chamber wall within the space cut off by the baffles from the main part of the 125 130

5 drying chamber. This supplemental or auxiliary heating means preferably comprises a plurality of pipes γ which are arranged on the wall of the drying chamber below the peripheral baffle, as shown in Fig. 2, and through which steam, hot water or other heating medium may be circulated.

10 After the machine has been running for a time and the space on the dry side of the drum adjacent to the scraper and below the baffles has become sufficiently heated, the steam may be turned off from the pipes γ inasmuch as the heat of the drum is sufficient to maintain a sufficiently high temperature to prevent condensation.

15 I claim as my invention:

1. A vacuum drier comprising a drying chamber, a drum rotatable in said chamber, and means for feeding liquid to said drum comprising a pan having a bottom, front and rear side walls arranged at opposite longitudinal edges of the bottom said front wall stopping short of the periphery of the drum while the rear wall engages the periphery of the same, and end walls arranged at the opposite transverse edges of the bottom and engaging with the periphery of the drum.

2. A vacuum drier comprising a drying chamber, a drum rotatable in said chamber, and means for feeding liquid to said drum comprising a pan arranged below the drum and adapted to support the liquid in position for the lower part of the drum to dip into the same, a manifold provided with a plurality of nipples opening into said pan, and a rocking support for said pan and manifold having its axis on one side of said manifold.

3. A vacuum drier comprising a drying chamber, a drum rotatable in said chamber, and means for feeding liquid to said drum comprising a pan arranged below the drum and adapted to support the liquid in position for the lower part of the drum to dip into the same, a manifold provided with a plurality of nipples opening into said pan, a rock shaft arranged on one side of the manifold, and a plurality of arms secured to said shaft and supporting said pan and associated parts.

4. A vacuum drier comprising a drying chamber, a drum rotatable in said chamber, and means for feeding liquid to said drum comprising a pan arranged below the drum and adapted to support the liquid in position for the lower part of the drum to dip into the same, a rock shaft provided with arms supporting said pan, a liquid supply conduit having a hollow swing arm which turns concentrically with said shaft, and a manifold connected with said swing arm and having a plurality of nipples connected with said pan.

5. A vacuum drier comprising a drying

chamber, a drum rotatable in said chamber, and means for feeding liquid to said drum comprising a pan arranged below the drum and adapted to support the liquid in position for the lower part of the drum to dip into the same, a rock shaft provided with arms supporting said pan, a liquid supply conduit having a hollow swing arm which turns concentrically with said shaft, and a manifold having two sections which have their inner opposing ends connected with opposite sides of said swing arm and each of which is provided with a plurality of nipples which are connected with said pan.

6. A vacuum drier comprising a drying chamber, a drum rotatable in said chamber, and means for feeding liquid to said drum comprising a pan arranged below the drum and adapted to support the liquid in position for the lower part of the drum to dip into the same, a rock shaft provided with arms supporting said pan, a liquid supply conduit having a hollow swing arm which turns concentrically with said shaft, and a manifold having two sections which have their inner ends connected with opposite sides of the swing arm while their outer ends are provided with removable caps and each of which is provided with a plurality of nipples whereby the same is connected with said pan.

7. A vacuum drier comprising a drying chamber, a drum rotatable in said chamber, and means for feeding liquid to said drum comprising a pan arranged below the drum and adapted to support the liquid in position for the lower part of the drum to dip into the same, a rock shaft provided with arms supporting said pan, a liquid supply conduit having a hollow swing arm which turns concentrically with said shaft and which has its inner end provided with a removable cap, and a manifold connected with said swing arm and provided with a plurality of nipples whereby the same is connected with said pan.

8. A vacuum drier comprising a drying chamber, a drum rotatable in said chamber, and means for feeding liquid to said drum comprising a pan arranged below the drum and adapted to support the liquid in position for the lower part of the drum to dip into the same, a rocking support for said pan, a manifold provided with a plurality of nipples connected with said pan, a stationary liquid supply pipe having a hollow knuckle, and a hollow swing arm connected with said manifold and having a knuckle which is rotatably connected with said stationary knuckle.

9. A vacuum drier comprising a drying chamber, a drum rotatable in said chamber, and means for feeding liquid to said drum comprising a pan arranged below the drum and adapted to support the liquid in posi-

tion for the lower part of the drum to dip into the same, a rock shaft having rock arms which support said pan, a stationary liquid supply pipe having a fixed hollow knuckle arranged concentrically with said shaft, a hollow swing pipe having a hollow knuckle which is rotatably connected with the knuckle of the stationary pipe, and a manifold connected with the swing pipe and the 10 pan.

10. A vacuum drier comprising a drying chamber, a drum rotatable in said chamber, and means for feeding liquid to said drum comprising a pan arranged below the drum 15 and adapted to support the liquid in position for the lower part of the drum to dip into the same, a rock shaft having rock arms which support said pan, a stationary liquid supply pipe having a fixed hollow knuckle arranged concentrically with said shaft and 20 which is engaged on one side by a collar on the shaft, a hollow swing pipe having a rotatable hollow knuckle which engages on one of its sides by a rotatable joint with the 25 other side of the fixed knuckle, a removable cap which closes an opening in the other side of the rotatable knuckle, and a manifold connecting said swing pipe with said pan.

30. 11. A vacuum drier comprising a drying chamber, a drum rotatable in said chamber, and means for feeding liquid to said drum comprising a pan arranged below the drum and adapted to support the liquid in position for the lower part of the drum to dip 35 into the same, a rock shaft having rock arms which support said pan, a stationary liquid supply pipe having a fixed hollow knuckle arranged concentrically with said shaft and 40 which is engaged on one side by a collar on the shaft, a hollow swing pipe having a rotatable hollow knuckle which engages on one of its sides by a rotatable joint with the 45 other side of the fixed knuckle, a removable cap which closes an opening in the other

side of the rotatable knuckle, a cross bar engaging with that side of an adjacent rock arm which faces the rotatable knuckle, stay rods arranged parallel with said shaft and connecting said rotatable knuckle and cross 50 bar on opposite sides of the removable cap, and a manifold connecting said swing pipe with said pan.

12. A vacuum drier comprising a drying chamber, a drum rotatable in said chamber, 55 means for supplying the liquid to be dried to the periphery of the drum, means for removing the dried material from the drum, and a baffle arranged between the drum and wall of the drying chamber above the removing means.

13. A vacuum drier comprising a drying chamber, a drum rotatable in said chamber, means for supplying the liquid to be dried to the periphery of the drum, means for removing the dried material from the drum, and a baffle arranged between the drum and wall of the drying chamber above the removing means comprising an inclined plate 65 connected at its upper edge with said wall, 70 and braces connecting the other edge of said plate with said wall and arranged below said plate.

14. A vacuum drier comprising a drying chamber, a rotatable drum arranged in said 75 chamber, means for supplying the liquid to be dried to the periphery of the drum, a scraper for removing the dried material from the drum, a baffle arranged between the periphery of the drum and the side wall 80 of the drying chamber above the scraper, and baffles arranged between the ends of the drying chamber and drum and extending along said scraper and peripheral baffle.

Witness my hand this 2nd day of June, 35 1910.
